United States Patent Office

Des. 175,737
Patented Oct. 4, 1955

175,737

CHENILLE FABRIC OR SIMILAR ARTICLE

Edwin Morgan and Theodore C. Sippel, Laurinburg,
N. C., assignors to Scotland Mills, Incorporated,
Laurinburg, N. C., a corporation of North Carolina

Application July 26, 1954, Serial No. 31,608

Term of patent 14 years

(Cl. D92—1)

FIG. 1.

FIG. 2.

We claim:

The ornamental design for a chenille fabric or similar article, as shown.
